UNITED STATES PATENT OFFICE.

HARRY T. MAZE, OF ANDERSON, INDIANA.

COMBINED HAIR BRUSH AND COMB.

1,272,982.

Specification of Letters Patent. Patented July 16, 1918.

Application filed March 23, 1918. Serial No. 224,308.

To all whom it may concern:

Be it known that HARRY T. MAZE, a citizen of the United States, residing at Anderson, in the county of Madison and State 5 of Indiana, has invented certain new and useful Improvements in Combined Hair Brushes and Combs, of which the following is a specification, reference being had to the accompanying drawings.

10 This invention relates to hair brushes, and particularly to a combined hair brush and comb.

The general object of the invention is to provide a combined hair brush and comb 15 so constructed that the hair may be combed out, at the same time it is brushed, thus saving the time and energy used in manipulating the brush separately.

A further object is to provide a combined 20 brush and comb in which the comb is disposed at the middle or axial center line of the brush and the bristles of the brush are disposed at an angle to the plane of the comb, so that one or the other of the sets 25 of bristles may be used with the comb, depending upon the direction in which the brush and comb are passed over the hair.

A further object is to provide a hair 30 brush of the character above described having a handle which folds with relation to the body of the brush, so that the brush may be folded into a very compact form for carriage.

A further object is to provide a brush with 35 a foldable handle, this foldable handle being so constructed and arranged that it will extend over and protect the comb.

Still another object is to provide a comb 40 engaging the body of the brush as before described, this comb being detachable from the body of the brush so that it may be renewed when desired or may be taken out for cleaning, or may be inserted in a new brush body.

45 Other objects will appear in the course of the following description.

My invention is illustrated in the accompanying drawings, wherein:

Figure 1 is a top plan view of a brush 50 constructed in accordance with my invention.

Fig. 2 is a transverse section thereof.

Fig. 3 is a side elevation of the brush with the handle open.

55 Fig. 4 is a like view of Fig. 3 but showing the handle closed.

Fig. 5 is a rear end view of the brush as shown in Fig. 4, and

Fig. 6 is a section on the line 6—6 of Fig. 3.

Referring to the brush and comb as illustrated in Fig. 1, 10 designates the body of the brush, this body being illustrated as of wood, though it may be of any suitable material and having its under face beveled toward the axial center plane of the body. The middle of the body is formed with a slot 11 or groove, which is preferably somewhat dove tail in form and disposed in this groove is the back 12 of a comb having teeth 13. 70 This back is slightly dove tailed in cross section so as to fit the dove-tail groove and interlock therewith. The body of the brush if formed on its under face with sockets for the reception of bristles 14, these bunches 75 of bristles extending in angular relation to the comb so that there will be one set of bristles on one side of the comb having their lower ends disposed in a plane parallel to the under face of the body 10 on that side 80 and the other set of bristles will be disposed in like relation to the under face of the body on the other side, and that planes intersecting the lower ends of the bristles will intersect the ends of the comb teeth. Preferably the bristles will be disposed at an angle of from 25 to 35° with relation to the comb. The body 10 may be without a handle, as is usual in the ordinary "Military" brush or may be provided with a handle such a 90 handle being illustrated in dotted lines in Fig. 1, and designated 15. Inasmuch as this form of brush is well known, it is not believed necessary to further illustrate it.

In Figs. 3 to 6, I show a brush of exactly 95 the same principle as heretofore described, but in which the construction is slightly different, the purpose being to provide a brush in which the handle is foldably connected to the body of the brush so that the brush 100 and handle may be folded into compact relation for insertion in a case or for packing. In these figures, 16 designates the body of the brush, which is beveled on its under face to provide two angularly related faces from 105 which project the bristles 17. The middle of the body 16 is engaged with the comb, 18, this comb being preferably T-shaped in cross section at its back, or dove-tailed in cross section and the groove for the reception of the comb being of the same cross sectional shape. One end of the body 16

is formed with a relatively narrowed portion 19 projecting beyond the body and extending downward parallel to the teeth of the comb, and this rear end of the body is 5 slightly recessed to receive a spring 20, which is illustrated as a leaf spring extending over the laterally reduced portion 19 of the body. The handle 21 is formed with a centrally disposed groove 22 which, when 10 the handle is folded over in the position shown in Fig. 4, receives and shields the teeth of the comb. One end of the handle is reduced in width as at 23, and slotted or bifurcated to embrace the reduced portion 15 19 of the body and is pivoted thereto by a rivet or other pivot member 24. It will be obvious now that when the handle is swung to the position shown in Fig. 3, the shoulder 25 will bear against the extremity of the 20 spring 20 and the spring 20 will bear against the reduced portion of the handle yieldingly holding it in alinement with the body, but permitting the handle to be folded over into the position shown in Fig. 4, to shield 25 the teeth.

I do not wish to limit myself to any particular shape for the brush as it may be rectangular or oval in plan view, nor to any particular arrangement of the bristles of the 30 brush, as it is obvious that these details may be changed in many ways, and furthermore I do not wish to be limited to the specific manner of mounting the handle 21 upon the body 16 as a collapsible or detachable handle 35 might be used with the body of the brush as well as a handle folding over so as to protect the teeth. I prefer, however, to so mount the handle that it will fold over into a position to protect the teeth and at the 40 same time render the brush compact.

It is also to be noted that the angle of the bristles makes it possible to use the comb in order to secure a proper part to the hair, without the bristles coming in contact with 45 the hair, and further that inasmuch as in the act of combing the bristles follow the

comb, my improved brush will help rid the hair of dandruff and loose hairs.

Having described my invention, what I claim is:

1. A brush including a body, and a comb projecting from the body and bristles extending from the body on each side of the comb, one end of the body being reduced in thickness and extending in the direction 55 of the comb teeth and parallel thereto, a handle having at one end an angularly disposed, U-shaped portion embracing the reduced portion of the body and pivoted thereto, whereby the handle may be turned 60 into a position beneath the comb teeth and parallel to the body or be rotated into a position in alinement with the body, and a spring tongue projecting from the body above the reduced portion thereof and 65 engaging with the U-shaped portion of the handle when the handle is turned into alinement with the body to hold the handle yieldingly in alinement with said body.

2. A brush including a body, a comb projecting from the body, bristles extending from the body on each side of the comb, a handle U-shaped in cross section and having at one end an angular portion, said angular portion being hinged at one end to the end 75 of the body, the handle being adapted to be turned into a position beneath the comb teeth and parallel to the body, or to be rotated to a position in alinement with the body with its angular portion abutted 80 against the end of the body to thereby limit the movement of the handle in a direction away from the comb teeth, and means mounted upon the body for yieldingly holding the body in alinement therewith.

In testimony whereof I hereunto affix my signature in the presence of two witnesses.

HARRY T. MAZE.
